CLAMPING MEANS.

Application filed February 15, 1923. Serial No. 619,161.

My invention pertains to drains for roofs or floors and relates to means for holding a "flashing" or the surface sheet of waterproof material in engagement with the drain. The object of the invention is to provide a means for the purpose mentioned which will not require perforation of the waterproof material or the provision of co-operating bolt or screw openings in the 10 clamping ring or drain. The invention is particularly applicable to and advantageous in connection with drains which have a recessed portion positioned below the surface to be drained and in which is seated a removable strainer.

In the accompanying drawings, Fig. 1 is a cross sectional view illustrating an embodiment of my invention; Figs. 2 and 3 are side and rear elevational views respectively of the clamp holding member and associated parts; Fig. 4 is a cross section on the line 4—4 of Fig. 3 and Figs. 5 and 6 illustrate a modified form of clamp holding means.

1 represents a drain body adapted to be positioned in a floor or roof and provided with a recessed portion in which is seated a removable strainer 2 provided with a circumferential flange 3 forming a sediment receiving cup and means for withdrawing from the drain sediment which collects in and above said cup and around the strainer. A sheet of waterproof material 4 which forms the top surface of the floor or roof extends over the perimeter of the drain body as shown and is held in clamped relation therewith by means of the annular clamping ring 5.

It has heretofore been the practice to hold the clamping ring in position by means of bolts or screws passing through it and through the waterproof material and into or through the drain flange. This construction has the disadvantages of requiring the 45 making of holes through the waterproof material, of the locating of the openings in the clamping ring, waterproof material and drain, in alignment for insertion of the clamping bolts and of difficulties in proportioning the length of bolts and extent of openings in the drain body to accommodate sheets of waterproof material of various thicknesses. To avoid the difficulties mentioned in the prior structure, I provide the drain body with integral spaced

lug 6 having a horizontally extending portion, through which a vertical opening is made; and on the wall of the drain body and in alignment with these openings, I provided locking teeth 7. The clamp holding member 8 has a vertical leg passing through the opening through the lug 6 and a horizontal leg extending over the clamping ring 5, the horizontal leg being provided with a set screw 9 in threaded engagement therewith and adapted to bear upon the clamping ring. I prefer to use either three or four clamp holding members suitably spaced apart.

The vertical openings in the lug 6 are 70 slightly over size with respect to the vertical leg of the clamp holding member 8 and the lower ends of these legs are provided with spaced notches for engagement with the teeth 7, whereby the clamp holding member can be adjusted vertically to accommodate for varying thicknesses of the waterproof material 4.

Pressure between the screw 9 and the clamping ring 5 causes the walls of the 80 openings in the lugs 6 to act as fulcrums, whereby pressure is applied to hold the co-operating teeth and selected notches in engagement, and thus a secure and satisfactory clamping of the waterproof material 85 between the periphery of the drain and the clamping ring is obtained. The play between the vertical leg of the clamp holding member and the opening through which it passes is sufficient to permit disengagement 90 of the teeth and notches and the adjustment or removal of the clamp holding member from the lugs 6 when desired.

In the modification shown in Figs. 5 and 6 wedging clamp 10 eccentrically mounted 95 on the horizontal leg of the clamp holding member 8 is substituted for the set screw shown in the other figures.

I claim:

1. In a device of the class described, the 100 combination of a drain body having a recessed portion provided with a water outlet, a sheet of water-proof material, an annular clamping member for holding said material in engagement with the drain body above 105 the recessed portion and means extending into the recessed portion and engaging with the clamping member and the drain to hold said member in clamping position, said means being located out of the surface of 110

the drain against which the water-proof material is clamped.

2. In a device of the class described, the combination of a drain, a sheet of water-proof material, a clamping member for holding said material in engagement with the drain, a clamp holding member, means on the drain body forming a vertical opening for the passage of the clamp holding member and inter-engaging locking means on said member and the inner lateral wall of said drain body.

3. In a device of the class described, the combination of a drain, a sheet of water-proof material, a clamping member for holding said material in engagement with the drain, means on the drain body located out of the surface of the drain against which the water-proof material is clamped and forming a vertical opening, an adjustable clamp holding member passing therethrough, and means for holding the clamp holding member in adjusted position.

4. In a device of the class described, the combination of a drain, a sheet of water-proof material, a clamping member for holding said material in engagement with the drain, means on the drain body forming a vertical opening, an L-shaped clamp holding member having one leg extending over the clamping member and the other passing through said vertical opening and engaging the drain body and means carried by the first mentioned leg of the clamp holding member to apply pressure to the clamping member, the opening through which the clamp holder passes being so positioned that its walls serve as a fulcrum whereby application of pressure between the clamping member and holder increases the engag-

ing pressure between the vertical leg of the holder and the drain.

5. In a device of the class described, the combination of a drain body provided with a recessed portion, a sheet of waterproof material, a clamp member for holding said material in engagement with the drain, an L-shaped clamp holder having its horizontal leg extending over the clamping member and its vertical leg extending into the recessed portion, means on the wall of the recessed portion forming a slightly oversized opening for the passage of said vertical leg, said vertical leg and the wall of the recessed portion being provided with inter-engaging teeth, a clamping screw in threaded engagement with the horizontal leg of the clamp holder and bearing upon the clamping member, the vertical planes of the passage-way, teeth, and clamping screw being in such relation that pressure between the clamping screw and the clamping member causes said teeth to be held in engagement.

6. In a device of the class described, the combination of a drain body, a sheet of water-proof material, an annular clamping member for holding said material in engagement with the surface of the drain body, and a clamp holding member having a vertical leg passing from a point below to a point above the clamping member and located within the inner edge of said member, said holding member being provided with a lateral extension projecting over the upper surface of the clamping member.

In testimony whereof, I have hereunto set my hand and affixed my seal.

JOSEPH HIRSHSTEIN. [L. S.]
